UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

1,121,002.

Specification of Letters Patent. Patented Dec. 15, 1914.

Application filed October 6, 1910. Serial No. 585,550.

To all whom it may concern:

Be it known that I, CHARLES E. DAVIS, a citizen of the United States, residing at Chicago, in the county of Cook and State of Illinois, have invented a certain new and useful Improvement in Mining-Machines, of which the following is a specification.

This invention relates to mining machines, and has for its object to provide a new and improved device of this description.

The invention is illustrated in the accompanying drawings, wherein—

Figure 1 is a plan view of one form of a mining machine embodying the invention; Fig. 2 is an enlarged side elevation of the device of Fig. 1; Fig. 3 is a sectional view taken on line 3—3 of Fig. 2; Fig. 4 is a sectional view taken on the line 4—4 of Fig. 3; Fig. 5 is a sectional view taken on the line 5—5 of Fig. 3; Fig. 6 is a view similar to Fig. 5 showing the parts in their inoperative position; Fig. 7 is a sectional view taken on the line 7—7 of Fig. 3; Fig. 8 is a sectional view taken on the line 8—8 of Fig. 3; and Fig. 9 is a sectional view taken on the line 9—9 of Fig. 8.

Like numerals refer to like parts throughout the several figures.

As illustrated in the drawings the machine is provided with two frames, a stationary frame 1 resting upon suitable supports, and a movable frame 2 carrying the cutting chain 3. In the particular construction shown, the movable frame also carries the motor 35 and the chain driving mechanism. In the operation of the device, the movable frame carrying the chain is fed forward against the coal so that the chain undercuts the coal. At the front of the stationary frame is a holding jack or part 4 mounted on a rod 5 so as to be free to slide therealong. Connected with the jack is a locking projection 6 adapted to fit into grooves 7 at the front of the stationary frame. When the jack is in the position shown in Fig. 2 the locking projection 6 is moved out of the groove 7 so that the jack may be slipped along the rod 5 to vary its position. When the locking projection is opposite one of these 50 grooves and the jack is lifted to strike the top or wall of the mine the locking projec-

tion passes into one of the grooves and locks the jack against movement along the rod 5.

Referring to Fig. 1, it will be noted that the chain projects beyond the stationary frame at the front of the machine, and I prefer to provide the movable or hinged protecting parts 8 which project beyond the chain when in their operative position, so as to protect it and act as safety devices which prevent the operator from being struck by the chain.

The chain and movable frame are moved forward by means of the gears 9 and 10 carried by the movable frame and which engage the racks 11 and 12 fastened to the stationary frame. The gears 9 and 10 are connected with a shaft 13 carried by the movable frame. Loosely mounted on this shaft are the gears 14 and 15, one of which, the gear 15, is adapted to move the frame forward and the other to move said movable frame backward. A clutch 16 is slidably mounted on the shaft and feathered thereto and is adapted to alternately engage the clutch members associated with the gears 14 and 15 so as to connect either of said gears with the shaft 13. The gear 14 is connected with the gear 17 on the shaft 18. The shaft 18 is connected by a worm gear 19 and worm 20 with the upright sleeve 21 surrounding the stationary upright shaft 21^a. This sleeve is driven from the motor shaft 22 (see Fig. 4) by the gears 23 and 24 and the beveled gears 25 and 26. An automatic safety device is provided with the motor and the chain feeding mechanism so that when the strain becomes too great the feed will be automatically stopped.

As herein shown, the worm gear 19 is loosely mounted upon the shaft 18. Associated with the gear 19 is a ring or part 27 fixed to the shaft 18 (see Figs. 8 and 9). Associated with the part 27 is a pin 28 which projects through a projection 29 and is held in place by a set screw 30. There is also mounted on the part 27 a pivoted arm 31 movably held in place by the part 32. This movable arm, when the device is in operation, engages the pin 28 and is provided with a beveled face 33 which is engaged by

a beveled face 34 associated with the gear 19. As herein shown, the gear 19 has attached thereto an engaging part 35 which carries the beveled face 34. It will be noted that the shaft 18 is driven by the gear 19 through the pivoted arm 31, pin 28 and part 27. The engagement between the beveled faces 33 and 34 forces the pivoted arm 31 to the pin 28 and when the pressure reaches a predetermined amount the pin 28 is broken and the arm 31 forced out of engagement with the gear 19, thus disconnecting the feeding mechanism from the motor. It will be noted, that by means of this construction a comparatively small pin 28 may be used because this pin does not bear all of the driving pressure, part of such pressure being transmitted to the part 27 through the arm 31 and pin 32. The size of the pin 28 will depend upon the incline of the beveled faces 33 and 34. By using a small pin 28 the cost is very materially reduced, the insertion of new pins made easy and the danger of injury to the mechanism by the broken pin materially reduced. The clutch 16 is arranged so as to be automatically thrown at each end of the machine so as to alternately connect gears 14 and 15 to the shaft 13. As herein shown, the clutch has a sliding ring 36 with pins 37 which are engaged by the arms 38. Connected with the arms 38 is an arm 39, the parts being mounted upon a shaft 40. The arm 39 engages stops 41 at the front and rear of the machine so as to automatically swing the clutch back and forth to alternately connect the gears 14 and 15 with the shaft 13.

Some means is provided for moving the machine from place to place. As herein shown, a drum 42 is carried by a shaft 43. This drum is adapted to receive a chain 44 or other flexible power transmitting device which can be fastened to a fixed point so that when the drum is rotated the entire machine will be moved bodily. In order to facilitate the side movement of the machine the frame is provided with the curved engaging faces 45. As herein shown, the shaft 43 is driven by the following mechanism:—Said shaft is provided with a gear 46 which engages a gear 47 rotatably connected with an arm 48 movably mounted upon the shaft 43 and adapted to be moved into and out of engagement with the gear 14. The arm 48 has connected with it a projection 49. The arm 48 and projection 49 form, as it were, a movable bracket carrying the gear 47, and by means of which it is controlled. There are preferably two arms 48 and projections 49 between which the gear 47 is mounted (see Fig. 3). The projections 49 are connected by links 50 with a controlling part 51, the connection being made by pins 52 and 53. The controlling part 51 is provided with a stop 54 which

engages the pin 52 when the gear 47 is in mesh with gear 14 (see Fig. 5). A spring 55 is associated with the controlling part 51 and is arranged so that when the parts are in the position shown in Fig. 5 where the gear 47 is in mesh with the gear 14 so as to drive the shaft 43, said spring pulls said gears into mesh, the pressure being transmitted from the gear 47 to the spring through the parts 49 and 50. If now, the pull in moving the machine becomes too great so as to endanger the teeth of the gears, the gear 47, being elastically pressed toward the gear 14 by the spring 55, is free to slip back and let the teeth of the gears slide past each other without driving the propelling mechanism. This construction, therefore, acts as a safety device to prevent injury to the mechanism and automatically relieve the strain. If the parts of the propelling mechanism are in the position shown in Fig. 5 and the gear 47 is moved to engage the gear 14 and the teeth are not in mesh, the gear 47 will give or be moved back so that one gear may be rotated until the teeth do come into mesh.

When it is desired to disconnect the drum 42 from the motor, the gear 47 is moved out of mesh with the gear 14. This may be done by moving the controlling part 51 to the position shown in Fig. 6. This part is provided with a socket 56 for a removable shifting bar 57. When the part 51 is moved outwardly so that it and the part 50 are inclined in a direction opposite to that shown in Fig. 5, the spring 55 assists in the further movement. Said spring also holds the parts in the position shown in Fig. 6.

While the mechanism for moving the machine bodily is in operation, it is desirable to connect the stationary and moving frames together so that the gears 47 and 14 may be held in mesh. In the drawing, this is done by means of the locking part 58 which is pivotally connected to the moving frame and which is adapted to engage the locking projection 59 on the stationary frame (see Fig. 4). The clutch 16 is moved by means of a shifting bar 60 which is inserted in a hole in the shaft 40. (See Fig. 4.) The locking part 58 is arranged so that when it is in its locking position as shown in dotted lines in Fig. 4, this hole is covered by it so that the shifting arm can not be inserted. The locking part has a hole 61 which registers with the hole in the shaft 40 when the locking part is in its inoperative position as shown in Fig. 4, said locking part being held in its operative position when the shifting bar is in place. When the propelling mechanism by which the machine is moved from place to place is being operated and the clutch is in its central or neutral position, it will be

seen that the movable frame can not be connected with the motor so as to move it forward until the two frames are disconnected.

I claim:

- 5 1. A mining machine comprising a stationary frame and a movable frame, a motor associated therewith, a mechanism associated with the frames for moving them relatively, a propelling mechanism forming part 70
10 of the machine for moving the entire machine from place to place, said propelling mechanism normally disconnected from the motor, and means for connecting said propelling mechanism with the motor under 75
15 predetermined conditions.
2. A mining machine comprising a stationary frame and a movable frame, a motor associated therewith, a mechanism associated with the frames for moving them 80
20 relatively, a propelling mechanism for moving the entire machine from place to place, means for connecting said propelling mechanism with the motor under predetermined conditions, and a locking attachment for 85
25 locking the stationary and movable frames together while the propelling mechanism is in operation.
3. A mining machine comprising a stationary frame and a movable frame, a motor 90
30 associated therewith, a mechanism associated with the frames for moving them relatively, a propelling mechanism for moving the entire machine from place to place, means for connecting said propelling mechanism with the motor under predetermined 95
35 conditions, a locking attachment for locking the stationary and movable frames together while the propelling mechanism is in operation, and means for preventing the 100
40 mechanism which moves the frames relatively from being set in operation while the two frames are locked together.
4. A mining machine comprising a stationary frame and a movable frame, a cutting 105
45 chain mounted on the movable frame, a motor also mounted on said movable frame, operating mechanism for moving the two frames relatively, a propelling mechanism on the stationary frame by means of which 110
50 the entire machine is moved from place to place, and means for connecting said propelling mechanism with said motor under predetermined conditions.
5. A mining machine comprising a stationary frame and a movable frame, a motor 115
55 associated therewith, a mechanism associated with the frames for moving them relatively, a propelling mechanism for moving the entire machine from place to place, 120
60 said motor adapted to be connected with said propelling mechanism under predetermined conditions, and a safety device adapted when the strain on the propelling mechanism reaches a predetermined point to automatically relieve such strain, said safety de- 125
65

vice comprising three toothed wheels, one connected with the motor and the other with the propelling mechanism, the third gear mounted upon a movable axis.

6. A mining machine comprising a stationary frame, a movable frame, a motor associated with said frames, means for connecting the motor and frames together so that said frames may be moved relatively, a propelling mechanism adapted to move the 75
entire machine from place to place comprising a drum carried by one of said frames, a shaft therefor, a gear on said shaft, a gear on the other frame operatively connected with said motor and an intermediate mov- 80
ably mounted connecting gear adapted to be moved to connect and disconnect said drum from said motor.

7. A mining machine comprising a stationary frame, a movable frame, a motor 85
80 associated with said frames, means for connecting the motor and frames together so that said frames may be moved relatively, a propelling mechanism adapted to move the entire machine from place to place comprising a drum carried by one of said frames, a shaft therefor, a gear on said shaft, a gear on the other frame operatively connected with said motor and an intermediate movably mounted connecting 90
95 gear adapted to be moved to connect and disconnect said drum from said motor, said movably mounted gear elastically held in its operative position so that it may give, when a predetermined pressure is applied thereto. 100

8. A mining machine comprising a stationary frame, a movable frame carried by the stationary frame and adapted to move therealong, a motor adapted to move the movable frame along the stationary frame 105
and automatic means for locking the two frames together under predetermined conditions.

9. A mining machine comprising a stationary frame, a movable frame, a motor 110
115 connected with said movable frame, a cutter mounted on the movable frame and operatively connected with said motor, a propelling mechanism for moving the entire machine from place to place mounted upon the stationary frame, and means for elastically connecting the propelling mechanism with the motor. 115

10. A mining machine comprising a stationary frame, a movable frame mounted 120
upon the stationary frame and adapted to move therealong, a motor on the movable frame, propelling parts on the stationary frame, automatic means for locking the two frames together under predetermined 125
conditions, and means for connecting the motor with the propelling parts when the frames are locked together.

11. A mining machine comprising a stationary frame, a movable frame, a motor 130

mounted on the movable frame, a driving device on the movable frame, propelling parts mounted on the stationary frame and a movable connecting device for connecting the propelling parts on the stationary frame with the driving device on the movable frame.

Signed at Chicago, Illinois, this 15th day of September, A. D. 1910.
